CLAIM

I claim the ornamental design for a electronic device stand with camera, speakers and microphone, as shown and described.

DESCRIPTION

FIG. 1 is a perspective view of a electronic device stand with camera, speakers and microphone, showing my new design;

FIG. 2 is a bottom plan view of FIG. 1;

FIG. 3 is a top plan view of FIG. 1;

FIG. 4 is a left-side elevational view of FIG. 1;

FIG. 5 is a right-side elevational view of FIG. 1;

FIG. 6 is a front elevational view of FIG. 1;

FIG. 7 is a rear elevational view of FIG. 1;

FIG. 8 is a perspective view, shown in an alternative position thereof;

FIG. 9 is a left-side elevational view of FIG. 8; and,

FIG. 10 is a right-side elevational view of FIG. 8.

The broken lines illustrate portions of the electronic device stand with camera, speakers and microphone which form no part of the claimed design.
